Moses Davenport's
Letter Patent

The Schedule referred to in these Letters Patent and making part of the same containing a description in the words of the said Moses Davenport himself of his improvement in the horse power for propelling machinery.

To all to whom these Presents shall come

Be it known that I Moses Davenport of Phillips in the County of Somerset and State of Maine have invented a new and useful improvement in the "Horse Power" Machine and that the following is a full and exact description of the construction and operation of the said machine as invented or improved by me. A frame is to be constructed of suitable timber to be about Eleven feet in length by about three feet and eight inches in width (and as there is to be an inclination throughout the length, the lower end may be about five feet high and the latter one six, from the sides to the ends there will be bars to steady the frame). At each end of this inclined frame, are to be placed cylinders or rollers, one at each end, constructed by placing at each end of an iron axle or shaft upon which the cylinder is to be revolved, a circular head of say, about three inches wide connected with the opposite one by means of a cross bar (lapping between and let into each). These heads are laid off into two parts on the circumference, one of which on the outside is formed into a six or nine sided figure or hexagon, the other into a twelve or more sided or dodecagon on which the links and bonds of the chain are to run, while the first is intended for the main bars (a cross the chain) to work on (will be about eighteen inches in diameter the cylinder being about three feet long). On the out side of each head is to be secured on to each side of the hexagon, a bar extending from the centre as a radius far enough beyond the circumference to form a tooth or say, on which the main bar is to drop (and work) on the inside of an iron end in bolt passing through the axle and secured up each side on the head as a way part of the axle. The cylinder at the top of the frame has on the outside of one end a large pulley either for a single or double band (about four feet in diameter and at the other,

around; the axles play in boxes secured on to the side pieces of the frame which are placed nearly half way up the perpendicular posts. Between these cylinders are placed, (and at a short distance from each) two cross pieces extending from side to side. On these are placed lengthwise of side by side two sets of rollers; made by setting up two narrow pieces edgewise from three to six inches apart having friction rollers of that length of six or seven inches diameter between them, whereupon axles turn in these said narrow pieces, the ends of which rest on the cross pieces abovementioned. Around these two cylinders, is to revolve an end left chain or jointed platform, constructed in the following manner intended for the horse or horses to walk on. Main bars or broad flat cross-pieces are to be provided of about three feet or such length as to reach from outside cog to the same on the opposite end of the cylinder, & to be about six or more inches wide and about one inch thick, as many in number as will reach around the cylinders and spaces between them these are to be connected by means of a chain formed by screwing on to each under side, and near each end a bent strap of iron about five inches long when doubled over at each end thereof, so as to enclose a square link of chain by one of its sides; and which is also to be so placed that the centre thereof is between the adjoining bars so that one half of the link rests beneath one and the other half beneath the other bar. The other end of the strap encloses another square link situated in the same manner; to which is again attached another strap &c &c, thereby forming a continued chain around the cylinders and beneath the main bars a chain being adapted to each end of the cylinders to work over that part thereof which forms the twelve sided figure and thus forms the connecting joint between the main bars; - each bent or double strap being screwed to the bar at the two ends in which are enclosed the sides of the square links. Above or on the top of the bars (and immediately over the chain) is disposed all along the line thereof a row of diamond shaped cleats or supports one to each bar, they are placed in a continuous row side by side the length of each one such as to extend across the width of each main bar half a nearly so over each adjoining one the direction of the length is to be that which (as the ends are to be cut off) a line parallel with the ends of the

main bay) give the diamond appearance. — Each cleat is attached to its bar by two screws which are to be one and the same as those used to fasten on the double straps — the screw being long enough to go through the strap, the bar of the cleat, (and in this way) to form a support on endless chain or jointed platform which is also to rest on the double row of friction rollers bearing against the under side of the top part of this chain or platform. Between two cog pieces forming the tops at the ends of the main frame is laid parallel with the sides, two long bars at a sufficient distance apart for a horse to travel between them & to reach about as high as his sides intended to secure the breaking to & to steady his motion, or it may be adapted for many. The end of each main bar of the platform, have a sufficient width mortised out of the centre to receive the cogs on the outside of the head, to drop into them as the platform moves on which enables the turning of the cylinder. Operation. The horse or horses, being placed on the platform & secured to the breaking hooks, the motion produced by walking on travelling bars placed on the tops of the main bars to prevent them from wear sets the jointed platform in motion (and the weight of the animal power is sustained by the double set of friction rollers beneath, & also by the diamond cleats above the platform. The links connected by the iron straps form a chain of joints to the main bars (and revolve round the twelve-sided figure of the cylinder heads while the cogs which project from these heads are caught by the mortises in the main bay (and consequently caught round with them which gives the desired motion to the said cylinder). A leather belt may be used instead of the chain & fastened on to the main bay by means of two screws in the same line of the length of the bay situated near the front edge of the unitite; so that first presented to the cog so as to keep it down steady to the cog & each belt has that part of the head it is to work over made in to a circular form, the strength of it being equal (where two are used) to about that of a thoroughbrace to a carriage spring (and the width may be from two to three inches) of small pieces of sheet iron at the insertion of each iron head in order to prevent its tearing through the leather. The front cylinder applies motion to the crank at one end & to the band wheel at the other which the power is continued on to the machinery intended to be driven.

inv. Do testimony that the above is a full and exact description of the construction and mode of operation of my improvement as invented or combined by me I have hereunto set my hand this twenty eighth day of August Eighteen hundred and thirty five. (and what I claim as my invention therein and not previously known or used is the method of construction or combination by which I have put together the several parts of the jointed platform of the cylinder heads & of the two sets of friction wheels.
